(57) CLAIM

The ornamental design for a feminine swimming suit, as shown and described.

DESCRIPTION

FIG. 1 is a perspective view of a feminine swimming suit embodiment my new design;

FIG. 2 is a front view thereof;

FIG. 3 is a back view thereof;

FIG. 4 is a left side view thereof, the right side being a mirror
image thereof;

FIG. 5 is a top view thereof; and,

FIG. 6 is a fragmented perspective view showing the upper torso of the feminine swimming suite.

The broken lines showing a human form is for illustrative purposes only and form no part of the claimed design.
